Renk

[11] Patent Number: Des. 417,661

[45] Date of Patent: ** Dec. 14, 1999

[54] MEMORY STORAGE COMPONENT

[75] Inventor: Thomas Edward Renk, Indianapolis, Ind.

[73] Assignee: Thomson Consumer Electronics, Inc., Indianapolis, Ind.

[**] Term: 14 Years

[21] Appl. No.: 29/085,842

[22] Filed: Mar. 31, 1998

[51] LOC (6) Cl. 14-02

[52] U.S. Cl. D14/114

CLAIM

The ornamental design for a memory storage component, as shown and described.

DESCRIPTION

FIG. 1 is a front elevational view of a first embodiment of a memory storage component showing my new design; FIG. 2 is a right side elevational view thereof; FIG. 3 is a left side elevational view thereof; FIG. 4 is a top plan view thereof, the bottom plan view being identical to the top plan view; and FIG. 5 is a front, right, and top perspective view thereof. FIG. 6 is a front elevational view of a second embodiment of a memory storage component showing my new design; FIG. 7 is a left side elevational view thereof; FIG. 8 is a right side elevational view thereof; FIG. 9 is a top plan view thereof, the bottom plan view being identical to the top plan view; and, FIG. 10 is a front, left, and top perspective view thereof.
